FLUID PRESSURE PRODUCING DEVICE

Erwin F. Loweke, Detroit, Mich., assignor to
Hydraulic Brake Company, Detroit, Mich., a
corporation of California

Application July 29, 1940, Serial No. 348,298

5 Claims. (Cl. 60—54.6)

This invention relates to fluid pressure braking systems, and more particularly to fluid pressure producing devices for such systems.

Broadly the invention comprehends a fluid pressure braking system including a fluid pressure producing device of the two-stage type operative to displace a large volume of fluid under low pressure and a relatively small volume of fluid under high pressure, and to gradually effect a transition from low to high pressure without proportionately increasing the applied or operative force.

An object of the invention is to provide a fluid pressure system including a fluid pressure producing device having means inhibiting accumulation of air and gas bubbles in the system.

Another object of the invention is to provide a fluid pressure braking system including a fluid pressure producing device comprising means for maintaining a predetermined pressure on the fluid in the system and so controlling the flow of fluid as to dispel any air or gas bubbles that may develop therein.

Other objects and advantages of the invention will appear from the following description taken in connection with the accompanying drawing, in which—

Fig. 1 is a schematic view of a fluid pressure braking system embodying the invention;

Fig. 2 is a vertical sectional view of a fluid pressure producing device incorporated in the system; and

Fig. 3 is a sectional view substantially on line 3—3, Fig. 2.

Referring to the drawing for more specific details of the invention, 10 represents generally a fluid pressure producing device including a reservoir 12, having a filling opening 14, normally closed as by a plug 16 provided with openings 18 for venting the reservoir to the atmosphere.

A cylinder 20 at the base of the reservoir includes a small chamber 22 and a relatively large chamber 24 arranged forward of the small chamber, concentrically thereto, and in direct communication therewith, and providing at its junction with the small chamber an annular shoulder 26.

The small chamber 22 is open at its outer end, and arranged in the wall thereof are spaced ports 28 and 30 providing communications between the reservoir and the small chamber, and the large chamber 24 is closed at its outer end by a head 32 provided with a discharge port 34 controlled as by a two-way valve indicated generally at 36.

As shown, the head 32 has a concentrically

disposed chamber 38 communicating with the chamber 24 and the discharge port 34. A shell 40 suitably secured in the chamber has a head 42 provided with a concentric opening 44 and a valve seat 46 on its back surrounding the opening. A valve 48 for cooperation with the seat 46 is normally urged to closed position by a spring 50 interposed between the valve and the head 32. The valve 48 includes a cylindrical body portion 52 slidable in the shell 40. This body portion has a section 54 of reduced diameter extended through and movable in the opening 44 in the head of the shell, and extended axially from the section 54 is a valve stem 56 concentrically disposed with relation to the chamber 24, the purpose of which will hereinafter appear. At the juncture of the body portion 52 and the reduced section there is provided a shoulder 58 having a profile corresponding to that of the valve seat 46 for cooperation therewith.

The body of the valve 48 has a concentrically disposed chamber 60 communicating with a passage 62 extended through the stem 56. A plug 64 closes one end of the chamber 60, and a passage 66 through the plug is controlled by a ball valve 68 urged to its seat by a spring.

A piston 70 reciprocable in the cylinder 20 is held against displacement by a washer 72 seated on an annular shoulder in the open end of the chamber 22 and secured in place by a retaining ring 74 seated in a groove in the wall of the cylinder.

The piston 70 includes a head 76, a reduced body portion 78 providing in conjunction with the wall of the chamber 22 an annular chamber 80 communicating with the reservoir 12 as by way of the port 28, and a skirt 82 supporting a sealing cup 84 for inhibiting seepage of fluid from the cylinder past the piston, and arranged in the back of the piston is a socket 86.

The head 76 of the piston has a plurality of spaced passages 88 therethrough providing communications between the annular chamber 80 and that portion of the chamber 22 forward of the head 76 of the piston, and a sealing cup 90 positioned on the head 76 controls the passages 88. A concentric extension 92 on the piston head 76 supports a piston head 94 reciprocable in the chamber 24. The head 94 and the extension 92 are concentrically bored to provide a passage 96 communicating with the chamber 22 by way of a restricted port 97. This passage receives the stem 56 of the valve 48 and communicates with the passage 62 therethrough, and the piston head 94 has a plurality of spaced passages

88 therethrough providing communications between the chambers 22 and 24. A sealing cup 100 sleeved on the valve stem 86 and seated on the piston head 84 controls the passage 88, and is adapted to provide a sealing means about the stem 86, and a spring 102 interposed between the cup and the head 84 of the cylinder serves to retain the cup against displacement and also to return the piston to its retracted position.

10 A fluid pressure delivery pipe or conduit 104 is suitably connected to the discharge port 34 has branches connected respectively to fluid pressure actuated motors 106, preferably arranged in pairs, one pair for actuating brakes associated with the front wheels of a vehicle, and another pair for actuating brakes associated with the rear wheels of the vehicle.

15 As shown, the brakes are of conventional type each including a fixed support or backing plate 108, a rotatable drum 110 associated with the backing plate, a pair of friction elements or shoes 112 pivoted on the backing plate for cooperation with the drum, a retractile spring 114 connecting the shoes, and a motor corresponding to the motors 106 mounted on the backing plate and connected to the shoes and operative for activation of the shoes into engagement with the drum against the resistance of the retractile spring.

20 A thrust pin 116 has one end seated in the socket 88 in the back of the piston 78, and on the other end of the thrust pin is a coupling 118 connected by a flexible boot 120 to the open end of the chamber 22 for the exclusion of dust from the cylinder. The coupling 118 receives one end of a rod 122, and the other end of the rod is pivotally connected to a foot pedal lever 124 rockable on a stub shaft 126 and connected as by a retractile spring 128 to a fixed support.

25 In a normal operation, upon depressing the foot pedal lever 124, force is transmitted therefrom through the rod 122 and thrust pin 116, to the piston 78, resulting in movement of the piston on its compression stroke. During the initial movement of the piston on its compression stroke, the cup 88 closes the port 80, and fluid in the chamber 24 forward of the piston head 84 is displaced therefrom, past the valve 48, through the discharge port 34 and fluid pressure delivery line or conduit 104 and the respective branches thereof into the fluid pressure actuated motors 106, causing energization of the motors with the resultant activation of the friction elements or shoes 112 into engagement with the drum 110 against the resistance of the retractile springs 114 to effectively retard rotation of the drums.

30 During initial actuation of the piston, a large volume of fluid is rapidly displaced from the large chamber 24 past the valve 48 and through the discharge port 34 and fluid pressure delivery lines 104 into the motors 106. This results in quickly moving the brake shoes 112 into engagement with the drums 110, and, thereafter, upon further movement of the piston on its compression stroke the pressure on the fluid in the system forward of the piston rapidly increases. When the pressure on the fluid reaches a predetermined degree, the valve 88 cracks, and fluid is gradually metered past the valve 88 through the valve chamber 80, the passage 62 in the valve stem into the passage 86, thence through the restricted port 87, into the chamber 22, until the pressures on the fluid in the chambers 22 and 24 become equalized. Immediately upon equalizing the pressure on the fluid fore and aft of the piston head 84, the piston head 78 becomes effective

35 for increasing pressure on the fluid as the net effective pressure creating area of the piston heads 78 and 84 equals the area of the small piston head 78, with the consequent increase in unit pressure in the fluid pipe lines. During this operation the valves 48 and 88 remain continually open so that a communication exists at all times from the portion of chamber 24 ahead of the piston 84, past the valve 48-88 and valve 88-82-87-22 to the portion of chamber 24 back of piston 84.

40 Upon completion of a braking operation, the applied or operative force on the foot pedal lever is released, and the lever returns to its retracted position under the influence of the retractile spring 128. This results in retracting the rod 118 and thrust pin 116 and the consequent release of the piston 78, whereupon the spring 102 becomes effective to move the piston to its retracted position.

45 As the piston moves to its retracted position, a partial vacuum is created in the chamber 24. This results in drawing fluid from the reservoir 12 through the port 28 into the annular chamber 80, thence through the passages 88 in the piston head 78, past the cup 88, into that portion of the chamber 22 forward of the piston head 78, thence through the passages 86 in the piston head 84, past the sealing cup 100, into the chamber 24, completely filling the chambers.

50 During this operation, fluid is returning to the cylinder from the motors 106, and the fluid pressure delivery lines connecting the motors to the cylinder, under the influence of pressure on the fluid in the motors and fluid pressure delivery lines, introduced by the retractile springs 114. The pressure on the fluid so returning to the cylinder cracks the valve 88, and the fluid then flows past the valve 88 through the chamber 80, the passage 86 in the valve stem, the passage 86 in the piston and the restricted port 87 into the chamber 22. This results in the chamber 22 receiving a quantity of fluid in excess of its capacity, and this excess of fluid is displaced from the cylinder 22 through the port 80 into the reservoir.

55 It will be apparent that the valve 88 not only precludes air and gas bubbles from the cylinder, but also operates to compensate for expansion and contraction of the fluid in the system, due to temperature changes and also maintains a positive pressure on the fluid in the system.

While this invention has been described in connection with certain specific embodiments, the principle involved is susceptible of numerous other applications that will readily occur to persons skilled in the art. The invention is, therefore, to be limited only as indicated by the scope of the appended claims.

Having thus described the various features of the invention, what I claim as new and desire to secure by Letters Patent is, —

60 1. A fluid pressure producing device comprising a double diametral cylinder having a small chamber and a large chamber, a discharge port for one of the chambers, a valve for control of the discharge port having means for conveying fluid from the valve through at least one of the chambers, a piston reciprocable in the cylinder having heads commensurate with the respective chambers and a passage therethrough providing communication between the means and the small chamber.

65 2. A fluid pressure producing device comprising a double diametral cylinder having a small chamber, a large chamber forward of the small

chamber and a discharge port for the large chamber, a two-way valve for control of the discharge port having a hollow stem for delivery of fluid from the valve through the large chamber, a piston reciprocable in the cylinder having spaced heads commensurate with the respective chambers and a passage therethrough connecting the hollow stem with the small chamber.

3. A fluid pressure producing device comprising a double diametral cylinder having a small chamber, a relatively large chamber forward of the small chamber and in communication therewith and a discharge port for the large chamber, a two-way valve for control of the discharge port having a hollow stem for delivery of fluid from the valve through the large chamber, and a piston reciprocable in the cylinder having spaced heads commensurate with the respective chambers and a passage therethrough providing communication between the hollow stem and the small chamber.

4. A fluid pressure producing device comprising a double diametral cylinder having a small chamber, a relatively large chamber arranged forward of, concentric thereto, and in direct communication with the small chamber, and a discharge port for the large chamber, a two-way

valve for control of the discharge port having a hollow stem for delivery of fluid from the valve through the large chamber, and a piston reciprocable in the cylinder having spaced heads commensurate with the respective chambers and a concentric passage telescoping the stem of the valve and communicating with the small chamber.

5. A fluid pressure system comprising a reservoir, a double diametral cylinder supplied therefrom having a small chamber, a large chamber arranged forward of the small, and a discharge port for the large chamber, fluid pressure delivery means connected to the discharge port, fluid pressure actuated means connected to the delivery means, a two-way valve for the discharge port operative to maintain a positive pressure on the fluid in the fluid pressure actuated means, means carried by the valve for delivery of fluid from the valve through the large chamber, a piston reciprocable in the chamber having spaced heads commensurate with the respective chambers and a passage therethrough, communicating with the means carried by the valve and with the small chamber.
